United States Patent Office

Des. 185,760
Patented July 28, 1959

185,760

CHEST

John J. Lubberts and Lambert J. Mulder, Grand Rapids,
Mich., assignors to Thomasville Chair Company,
Thomasville, N.C., a corporation of North Carolina

Application May 20, 1959, Serial No. 55,994

Term of patent 14 years

(Cl. D33—6)

Fig. 1

Des. 185,760

PAGE 2

Fig. 2.

Fig. 3.

The sides are conventional. The back is plain and unornamented.

We claim:

The ornamental design for a chest, substantially as shown and described.
